UNITED STATES PATENT OFFICE.

WILLIAM LOUIS ST. JULIEN PRIOLEAU, OF LONDON, ENGLAND.

APPARATUS FOR EFFECTING THE DESTRUCTIVE DISTILLATION OF CARBONACEOUS MATERIAL.

1,237,094.

Specification of Letters Patent. Patented Aug. 14, 1917.

Application filed June 20, 1916. Serial No. 104,776.

To all whom it may concern:

Be it known that I, WILLIAM LOUIS ST. JULIEN PRIOLEAU, a subject of the King of Great Britain, residing at London, England, have invented certain new and useful Improvements in Apparatus for Effecting the Destructive Distillation of Carbonaceous Material, of which the following is a specification.

10 This invention relates to improvements in apparatus for effecting the destructive distillation of carbonaceous materials, in accordance with the process described in co-pending application 63,335, filed Nov. 24, 1915.

15 One object of the invention is to provide means for accurately controlling the temperature in each of a series of different zones in a retort according to the distillates required from the particular zones.

20 Other objects of the invention will appear more fully hereinafter.

The invention consists substantially in the construction, combination, location, and arrangement of parts, all as will be more fully hereinafter set forth, as shown in the accompanying drawing, and finally pointed out in the appended claim.

25 In the construction and operation of a distillation retort it has previously been proposed to withdraw different volatile products from different parts of the distillation retort heated to different temperatures, and quickly to condense such products simultaneously. The present invention relates to distillation apparatus operating on this principle; and it consists in a simple and effective construction and arrangement whereby the desired results are secured, and which will now be described more in detail.

30 Figure 1 of the accompanying drawing illustrates the improvement as applied to the invention of copending patent application Serial No. 63,335, filed November 24, 1915, and Fig. 2 is a plan view of the same. Referring to said drawings, *a* is a single chamber retort carried in a furnace setting having end walls *A* and *E*, and the partition walls, *B*, *C*, *D*, definitely dividing up 35 the surface heating flues into compartments *q*, *r*, *s*, *t*, and separate burners *u*, *v*, *w*, *x*, are arranged in the respective compartments, each controlled by a gas supply regulating valve *F*, *G*, *H*, *I*. A conveyer screw 40 is shown in the drawing for slowly conveying

ing the carbonaceous material through the retort in the known manner, but other means may be employed for this purpose.

The several supply pipes are connected to a main supply pipe *n*, which may in turn be supplied either from the gas supply *o*, coming from the retort *a* through the condensers, per the pipe *n'*, or from an independent supply *J*, or from both. The gases from pipe *n'* return to the pipe *n*, the gas being drawn by any suitable pump, such as the centrifugal pump *Z*, through the pipe *n'* and are delivered to the pipe *R* connecting to *n*; intermediately the gas is passed through cooling apparatus of any suitable known form—say a cylinder with water trays, or dropping spray—indicated by *Q*, in which its temperature is reduced so as to be again ready for use as a condensing medium when returned through the condensers *e*, *f*, *g*, *h*. This separates oil, tar, etc., carried by the gases leaving the pipe *n'*, which may have been only incompletely removed by the ejector condensers.

45 The gas passage preferably has a branch *S* through which gas is taken to the heating gas pipe *p* as it is not necessary to be cooled, if this is to be used for heating.

50 As above stated volatile matters are directly and simultaneously removed from the retort *a* by pipes *1*, *2*, *3*, *4*, such volatile matters varying according to the temperature in the several zones of the retort, and they are immediately condensed in a series of ejector condensers *e*, *f*, *g*, *h*, by cool gases supplied from the pipe *n* and the distillates removed through the pipes *i*, *j*, *k*, *l*.

55 K, L, M, N, are openings from each of the heating compartments into a common flue *T* to the chimney *O* arranged by the side of the retort, or some other convenient position, but by the use of dampers and auxiliary flues, or by connecting passages such as are shown dotted through the walls *B*, *C*, *D*, the hot gases may be carried from one 60 zone to another, dampers being provided in any usual form to vary the path of the combustion gases as desired. A suitable example of the flue design is indicated in Fig. 2; K, L, M, N showing the dampered openings to the flue *T*, which may be of sheet metal, and *b*, *c*, *d* the dampers regulating the openings through the partition walls *B*, *C*, *D*.

65 Air for combustion may be conveniently

admitted by openings in the base wall beneath the burners, or as shown in Fig. 2, by openings U, V, W, X through the said walls, such openings being closed with removable fire bricks when not required, or by means of dampers of ordinary design.

The final product from the conveyer will be coke, and in order to get this of a harder character, a chamber shown dotted at t' 10 may be employed in which the coke coming out of the delivery chute is heated up to about 800 degrees C., the said chamber being provided with an additional heating burner y, controlled by valve Y.

15 Although a single conveyer chamber forms a unit in itself, there may of course be several units in a complete plant.

By means of this invention successive zones of the retort may proceed either with 20 a gentle and a successive temperature increase, or by temperature differences of considerable amount, or again by an increase and then a decrease as may be desired.

What I claim as new and useful and of my own invention, and desire to secure by 25 Letters Patent, is:—

In an apparatus for distilling volatile matters from solid carbonaceous material, the combination of an elongated retort, a plurality of heating compartments surrounding successive portions of the length thereof, thereby establishing zones in said retort, independently regulatable heating means in each of said compartments, a conveyer in the said retort for conveying a 30 solid material through the length of said retort, said conveyer substantially filling the cross-section of said retort, ejector condensers, a plurality of vapor outlets one connected to each of the several zones of 35 the retort, said outlets each being connected to an ejector condenser, and means for supplying cool gases to each of said ejector condensers.

In testimony whereof I affix my signature. 40

WILLIAM LOUIS ST. JULIEN PRIOLEAU.
